CLAIM

The ornamental design for a clock, as shown and described.

DESCRIPTION

The claimed clock is used for measuring or indicating time. It is a mechanical or electronic device which has moving hands and a moving figurine of a surfer which moves out of, and into, a wave, at alarm times.

FIG. 1 is a front elevational view of a clock showing my new design;

FIG. 2 is a right side view thereof;

FIG. 3 is a left side view thereof;

FIG. 4 is a rear elevational view thereof; and,

FIG. 5 is a top plan view thereof.

The portions shown in broken lines are included for illustrative purposes only and form no part of the claimed design.
